SHOE SHINE STAND OR SIMILAR ARTICLE

Charles G. Dallas, Woodbury, N. J.

Application February 13, 1956, Serial No. 40,153

Term of patent 14 years

(Cl. D9—2)

Fig. 1.

Fig. 2.

The original features of my design reside in the portions shown in full lines.

I claim:

The ornamental design for a shoe shine stand or similar article, substantially as shown and described.
